Primary Examiner — Darlington Ly(74) *Attorney, Agent, or Firm* — Shuttleworth & Ingersoll, PLC; Timothy J. Klima(57) **CLAIM**

The ornamental design for a tire tread, as shown and described.

DESCRIPTION

The patent or application file contains at least one drawing executed in color. Copies of this patent or patent application publication with color drawing(s) will be provided by the Office upon request and payment of the necessary fee.

1. **Tire tread**

1.1 is a perspective view of a tire tread embodying my new design;

1.2 is a front elevation view thereof;

1.3 is a right side elevation view thereof; and

1.4 is a partial and enlarged perspective view thereof.

The red colored showing the side wall of the tire is provided for the purpose of illustrating environmental structure and forms no part of the claimed design.
